SUMMARY BOARD

George H. Dawson, Chicago, Ill., assignor to
Wilson-Jones Company, Chicago, Ill., a cor-
poration of Massachusetts

Application December 20, 1933, Serial No. 403,176

4 Claims. (Cl. 120—33)

This invention relates to a summary board whereby a plurality of sheets may be suspended in horizontal overlapping relationship so that single columns on each of the suspended sheets may be held in juxtaposed positions to facilitate summarization of the data contained in the exposed columns. The invention relates particularly to means for aligning the sheets and for aligning the line guide with reference to the sheets.

It is an object of this invention to provide means for aligning a plurality of sheets impaled upon a ring bar. It is a further object of this invention to provide means for adjusting the angularity of a line guide to insure accurate alignment of the reading edge of the line guide with respect to the sheets impaled on the ring bar. Other objects of this invention will become apparent upon reading the following description taken in conjunction with the accompanying drawings in which:

Figure 1 is a perspective view of my summary board;

Figure 2 is a cross sectional view taken on the line II—II of Figure 1;

Figure 3 is a view similar to Figure 2 illustrating a modified embodiment of the ring bar;

Figure 4 is a view similar to Figure 2 illustrating another modified embodiment of the ring bar;

Figure 5 is a view similar to Figure 2 illustrating another modified embodiment of the ring bar;

Figure 6 is a fragmentary perspective view of the ring bar illustrated in Figure 5;

Figure 7 is a fragmentary perspective view illustrating the housing carrying the line guide;

Figure 8 is a top plan view of the housing with parts broken away to facilitate illustration of the structural details;

Figure 9 is a cross sectional view taken along the line IX—IX of Figure 8 looking in the direction of the arrows; and

Figure 10 is a cross sectional view taken along the line X—X of Figure 8 looking in the direction of the arrows.

In the drawings, the reference numeral 2 indicates a flat plate member adapted to be supported at any desired angle by means of an easel structure 3. The preferred easel structure does not constitute part of this invention and is fully described in United States Letters Patent No. 1,833,255 issued October 18, 1932 to Paul O. Unger. The flat plate structure will not be described in detail because it is fully described in the joint application of applicant and Paul O. Unger filed March 16, 1933 under Serial No. 661,080.

The flat plate member 2 is provided with a channel shaped depressed portion 4 adjacent its upper edge. This channel shaped depressed portion 4 is provided with a fixed lug 5 at one end and a sliding lug 6 at the other end and is adapted to receive a ring bar 7. The ring bar 7 is provided with open ends into which the lugs 5 and 6 are adapted to fit to secure the ring bar in the channel shaped depressed portion 4.

The ring bar 7 consists of a pair of toggle plates 8, 9 snugly mounted in a curved metal plate 10. A plurality of mating ring sections 11, 12 each have one end secured to the toggle plates. A plurality of buttons 13 are secured between the toggle plates to prevent either plate from jumping out of position when the ring sections are open or closed. A reinforcing member 14 is secured to the ring bar 7 in any suitable manner. The reinforcing member 14 is provided with a pair of depending flanges 15, 16, so that the ring bar may lie flat on a desk or table. The flanges 15, 16 also add rigidity to the reinforcing member 14. The above described structure is identical in each embodiment of the invention.

In the embodiment of my invention illustrated in Figures 1 and 2, the ring bar 7 is provided with a cover plate 17 which is adapted to cover the toggle plate mechanism and the edges of the curved metal plate 10. The cover plate 17 may be secured to the curved plate 10 by means of rivets (not shown) passing through both plates, or in any other suitable manner. The cover plate is preferably angular, as shown in Figure 2, but may be flat if desired. The edges of the cover plate 17 overlap the edges of the channel shaped depressed portion 4. The cover plate 17 is provided with a plurality of notches 18 adjacent its edges to allow the ring sections 11, 12 to pass therethrough.

A plurality of sheets 19 provided with spaced apertures 20 adjacent their upper edges are impaled on the rings 11, 12 and are maintained in overlapping relationship thereby. Generally, the rings are sufficient to maintain accurate horizontal alignment of the sheets because of the plurality of contacts between each sheet and the rings, but in cases where the sheets are extremely narrow, it is desirable to provide additional aligning means for the sheets. The preferred means consists of a plurality of aligning pins 21 secured to the cover plate 17 in any suitable manner such as spinning, riveting or welding. The aligning pins are preferably made of substantially the same diameter as the diameter of the apertures 20 so that the sheets fit snugly on the aligning

pins. The aligning pins 21 extend from the cover plate 17 in a plane parallel to the plane of the lower exposed portion of the rings 11, 12 so as to facilitate engagement of the sheets and pins. 5 The lateral movement of this portion of the rings in opening and closing is so slight, and the rings are so much thinner than the pins, that the parallelism between the pins and the lower portion of the rings is substantially maintained in 10 either open or closed position. The upper edge of each aligning pin 21 is beveled, as indicated at 22, to further facilitate the impalement of the sheets 19 on the pins.

In the embodiment of Figure 3, the aligning pins 21 are secured to an otherwise conventional ring metal cover plate 23. The outer edges 24 of the cover plate embrace the outer edges of the curved metal plate 10 and lie between the plate 10 and the reinforcing member 14.

20 The embodiment of the invention illustrated in Figure 4 includes a plurality of aligning pins 25 secured to the toggle plates 26, 27 in the same manner as the pins 21 are secured to the cover plates 17 and 23. The securing of the aligning pins directly to the toggle plates causes the aligning pins to be moved transversely with the rings 11, 12 in opening and closing the rings so that the parallelism between the pins and the lower exposed portion of the rings is more accurately maintained than in the embodiments 25 where the aligning pins are not moved.

In Figures 5 and 6, the ring metal 7 is provided with a cover plate 28 that has the end portions of its edges embracing the curved metal plate 10 and lying between the edges of the plate 10 and the reinforcing member 14. The intermediate edge portions 29 of the cover plate project beyond the edges of the plate 10 as clearly shown in Figure 5. Each edge of the ring bar is provided with a metal plate member 30 apertured to fit over the ring sections 11, 12. The aligning pins 21 are secured to the members 30 in the same manner as in the case of the cover plates 17 and 23. Each member 30 has a plurality of metal clips 31 welded or riveted thereto and adapted to embrace the edge portions 29 of the cover plate. The clips 31 are loose enough to permit transverse movement of the members 30 relative to the cover plate. When the rings are opened or closed, the members 30, and consequently the aligning pins 21, are moved with the ring sections just as in the embodiment of the invention illustrated in Figure 4.

55 In order to attain speed and accuracy in computing data from sheets mounted on a summary board, it is not sufficient merely to have the sheets aligned properly, but it is also necessary to have the line guide parallel with the line of figures being summarized. My line guide mechanism 60 includes a line guide 32 rigidly secured to a housing 33 adapted to travel up and down a rod 34 spaced from one end of the flat plate member 2 and secured in place by means of a pair of flat strips 35, 36 (Figure 1) extending from one end of the plate member 2 adjacent the top and bottom, respectively. The rod 34 is secured to the strips 35, 36 by means of screws or rivets. A portion of the peripheral surface of the rod 34 is serrated, as indicated at 37, Figures 8, 9 and 10.

70 A metal plate 38, U-shaped in cross-section, is mounted in the housing 33 on one side of the rod 34. A pair of rollers 39, 40 is mounted in the plate 38 by means of the studs 41, 42. The periphery of the roller 40 is serrated, as indicated at 43, to enable the roller 40 to mesh with the

serrations 37. A pair of coiled springs 44, 45 mounted between the plate 38 and the housing 33 exert a constant force against the plate 38 to maintain the roller 40 in positive engagement with the serrations 37. The springs 44, 45 are 5 positioned by means of the studs 46, 47. One end of the stud 42 is extended beyond the front wall of the housing 33 and carries a knob 48 which may be rotated to move the housing along the rod 34. The aperture in the housing through 10 which the stud 42 passes is slightly elongated, as indicated at 42', Figure 7 for a purpose to be hereinafter described.

A roller 49 is mounted in the housing 33 on the opposite side of the rod 34 by means of a stud 50. 15 A metal plate 51, U-shaped in cross-section, is mounted in the housing 33 on the opposite side of the rod 34 from the plate 38 by means of a stud 52. The stud 52 is spaced centrally of the plate 51 so that the plate 51 may be pivotally moved around the stud 52 as a center. Another roller 53 is mounted in the plate 51 adjacent its upper edge by means of a stud 54. A threaded stud 55 is rigidly secured to the plate 51 adjacent its lower edge and extends through one wall of 20 the housing 33. A threaded adjusting nut 56 is mounted on the portion of the threaded stud 55 outside the housing 33.

The angularity of the line guide 32 is adjusted simply by rotating the nut 56. If the free end of 30 the line guide is lower than the end secured to the housing, the nut 56 is rotated so as to move the lower edge of the plate 51 to the left (Figure 8). Since the rod 34 is fixed, the roller 53 cannot move to the right, and since the housing 35 and plate 51 are secured together by the stud 52, the plate 51 acts as a lever of the second class and pulls the upper edge of the housing to the left.

The lower edge of the housing cannot move 40 any substantial distance to the left because the slot 42' (Figure 7) is elongated only very slightly and the right end of the slot 42' soon contacts with the stud 42. In view of the fact that the roller 49 is fixed to the housing and cannot move to the right because it is in contact with the rod 34 which is also fixed, the roller 49 acts as a pivot point for the housing. The portion of the slot 42' extending to the left of the stud 42 permits the slight movement of the housing with respect to the stud 42 necessary to permit the counter-clockwise pivotal movement of the housing around the roller 49 as pivot. The rigid securing of the line guide to the housing causes the line guide to move angularly with the housing. 55 It will be understood that the apertures in the housing through which the rod 34 passes are sufficiently large to allow the slight movement of the housing necessary to adjust the angularity of the line guide.

The angular movement of the housing and line guide above mentioned compresses the spring 44. When the nut 56 is moved in the opposite direction from that described above, the spring 44 expands and moves the upper edge of the housing 65 to the right (Figure 8). The lower edge of the housing is prevented from moving to the right by the roller 49 which is fixed to the housing and is in contact with the rod 34. Accordingly the housing is pivotally moved in clockwise direction and the free end of the line guide is moved downwardly. Obviously, the degree of angular movement of the line guide in either direction can be controlled accurately by means of the threaded adjusting nut. 70

While I have described my invention in detail, it will be understood that the description thereof is illustrative, rather than restrictive, as many details may be modified or changed without departing from the spirit or scope of my invention. Accordingly, I do not desire to be restricted to the exact construction described, except as limited by the appended claims.

I claim:

- 10 1. In a ring bar for summary boards, a pair of toggle plates, a plurality of sheet retaining rings on said toggle plates, and a plurality of aligning pins intermediate said rings.
- 15 2. In a ring bar for summary boards, a pair of toggle plates, a plurality of sheet retaining rings

carried by said toggle plates, a cover plate, and a plurality of aligning pins carried by said cover plate.

3. A ring bar for summary boards, a pair of toggle plates, a plurality of sheet retaining rings carried by said toggle plates, and a plurality of aligning pins intermediate of said rings, said aligning pins being adapted to move transversely when said sheet retaining rings are opened or closed.

4. In a ring bar for summary boards, a pair of toggle plates, a plurality of rings on said toggle plates, a strip mounted on said rings, and a plurality of aligning pins carried by said strip.

GEORGE H. DAWSON. 15
